CLAIM

The ornamental design for a paint tray liner as shown and described.

DESCRIPTION

FIG. 1 is a perspective top-right view of an exemplary embodiment of the disclosed paint tray liner design;

FIG. 2 is a perspective top-right environmental view of the paint tray liner design of FIG. 1 shown in position to be placed in a paint tray;

FIG. 3 is another perspective top-right environmental view of the paint tray liner design of FIG. 1 shown in position in a paint tray;

FIG. 4 is a perspective bottom-right view of the paint tray liner design of FIG. 1;

FIG. 5 is a top view of the paint tray liner design of FIG. 1;

FIG. 6 is a bottom view of the paint tray liner design of FIG. 1;

FIG. 7 is a left side view of the paint tray liner design of FIG. 1;

FIG. 8 is a right side view of the paint tray liner design of FIG. 1;

FIG. 9 is a front view of the paint tray liner design of FIG. 1;

FIG. 10 is a back view of the paint tray liner design of FIG. 1;

FIG. 11 is a cross-sectional perspective top view of the paint tray liner design taken from line 11-11 in FIG. 5; and,
FIG. 12 is an enlarged partial view taken from line 12 in FIG. 11.

The broken lines in the drawings show the environment of the paint tray liner that form no part of the claimed design.
